Primary Examiner — Dominic Simone(74) *Attorney, Agent, or Firm* — Banner & Witcoff, Ltd.(57) **CLAIM**

The ornamental design for a shoe upper with tongue region, as shown and described.

DESCRIPTION

FIG. 1 is a front perspective view of a shoe upper with tongue region showing my new design;

FIG. 2 is a right side view thereof;

FIG. 3 is a left side view thereof;

FIG. 4 is a top view of thereof;

FIG. 5 is a front perspective view of the shoe upper with tongue region of FIG. 1 in an in-use configuration with the disclaimed lacing elements shown in broken lines;

FIG. 6 is a right side view thereof;

FIG. 7 is a left side view thereof; and,

FIG. 8 is a top view of thereof.

The broken lines showing circular eyelet regions in FIGS. 1-8 and the lacing elements in FIGS. 5-8 are for environmental purposes only and form no part of the claimed design. The broken lines showing the remainder of the shoe are for environmental purposes only and form no part of the claimed design.
